INVENTOR
Clarence D. Platt,

C. D. Platt

ATTORNEY

UNITED STATES PATENT OFFICE.

CLARENCE D. PLATT, OF BRIDGEPORT, CONNECTICUT.

INCLOSED SWITCH CATCH.

Application filed January 27, 1923. Serial No. 615,279.

To all whom it may concern:

Be it known that I, CLARENCE D. PLATT, a citizen of the United States of America, and residing at Bridgeport, in the county 5 of Fairfield and State of Connecticut, have invented new and useful Improvements in Inclosed Switch Catches, of which the following is a specification.

This invention relates to inclosed switches 10 and has for its object the provision of a simple, cheap, rugged, easily operated means for securely fastening the cover of the switch to the body of the box.

Fig. 1 is a plan view of a switch box 15 embodying my invention.

Fig. 2 is a side elevation of the box shown in Fig. 1.

Fig. 3 is a fragmentary end view of the box as seen from the left of Fig. 2.

Fig. 4 shows a blank from which the strap may be made, and

Fig. 5 shows a blank for an anchorage or catch.

In the drawings there is shown a switch 25 box of usual type comprising a body member 1 and a cover member 2 which may be connected thereto as by the hinges 3. The particular box shown has side walls 4 and end walls 5 intersecting to form corners.

The cover has a side flange 6 and two end flanges 7 adapted to overlie the corresponding walls of the body member of the box. Any desired type of electric switch may be mounted in the back of the box body, 35 a simple double pole switch 8 being shown in this case.

When the switch box has been installed and the connecting wires secured to their proper terminals, it is customary to close 40 the box cover and frequently desirable to provide means for locking the cover in closed position to prevent tampering with the switch connections. I provide for this purpose a strap 9 preferably made of sheet metal and means for connecting one end 45 of the strap to a convenient portion of the cover and the other one to an anchorage on the body. I bend the strap at a point intermediate its ends preferably at an angle of 45°. Thus the strap is adapted to lie flat against an end member and extend around the corner so as to also lie flat against a side member. By thus forming the strap 50 I am able to use the simplest type of fastening means to hold one end of the strap in proper position relative to one member, for

example, a rivet 10 may pass through a hole 11 near one end of strap 9 and through an end flange 7 of the cover, the end inside being upset. This construction permits the 60 strap to rotate freely so that its free end may swing flat against the side wall of the body around the corner from the rivet at which point a suitable anchorage is provided 65 to retain the strap. I provide the projection 12 preferably by striking up a lug from the material of the member and this projection 12 is adapted to extend through a slot 13 near the free end of strap 9. To hold the cover tight in closed position I preferably 70 make the edge of projection 12 which is engaged by the bottom edge of slot 13 cam shaped so that the bottom of slot 13 will at first lightly engage projection 12 when 75 moved from the dotted line position (seen at the right of Fig. 2) towards the locking position and as the free end is moved nearer to the member carrying the anchorage bracket, tension will be placed on the strap 80 until the cover is tightly closed. If desired, a notch 14 may be provided at the end of the cam surface to prevent accidental displacement of the strap after it has once been put in locking position. The projection 12 85 may be punched to receive a padlock or other suitable means for preventing removal of the strap therefrom. The strap and anchorage members are also provided with small holes for receiving a sealing 90 means.

As shown at the right end of the box the strap 9 may be riveted to a side wall of the box and the anchorage 12 may be around the corner on the end flange 7 of the cover. Obviously the strap might be riveted to a 95 side flange and the anchorage be located on an end wall of the box or it might be riveted to an end wall of the box and the anchorage located on a side flange of the cover. If desired straps may be provided at both ends 100 of the box arranged either symmetrically or in any desired combination. For convenience in lifting the strap from its anchorage I preferably bend one of the free corners outwardly from the box as shown at 105 15. The riveted end of the strap may be round as shown in Fig. 3 or square as shown in Fig. 4. The slot 13 will ordinarily be rectangular but might be of some other shape. Where a bracket as 16, is used to provide the anchorage it may be riveted or otherwise secured 110 to the box.

It will be noted that only three pieces are required to carry out this invention, the rivet or pivot, the strap and the anchorage, the first and last of which may be, if desired, integral with the box. The fastening is very secure since attempts to open the box without first unfastening it only force the strap more tightly into contact with the members of the box to which it is secured. 10 If desired, the cover need not be hinged to the body but be secured thereto most firmly by using two fastenings of the type described at diagonally opposite corners.

I claim—

- 15 1. In an inclosed switch, a box comprising a body having side and end wall members and a cover for the body having side and end flange members overlapping the edges of said body, a strap pivoted at one end to one of said members and extending around a corner of the box, and an anchorage for the strap secured to the other of said members.
- 20 2. In an inclosed switch, a box comprising a body having walls and a flanged cover therefor, a strap pivoted at one end to a flange for motion in a plane approximately parallel thereto, said strap being bent to extend around a corner of the box, and a catch on one of said walls to receive the other end of said strap and retain the same.
- 25 3. In an inclosed switch, a box comprising a body member and a cover member each having end and side portions at substantial angles to one another to form corners, a flat sheet metal strap having one part lying flat against one of said end portions of one member and hinged at one end thereto for rotation about an axis perpendicular thereto, said strap having its other end extending around a corner of the other member, and an anchorage carried by the other member to latch with said strap whereby the two members may be detachably interconnected.
- 30 4. In an inclosed switch a sheet metal box body having side and end walls, a cover hinged to the body and having side and end flanges to overlie the respective body walls, an angular strap having one end pivoted to a flange of said cover and a slot at the other end, a bracket projecting from one of

the walls of the box body around the corner from the pivoted end of said strap and adapted to receive an edge of the slot in said strap.

55

5. In an inclosed switch box a body member and a cover member therefor, said members each comprising two sheet metal plates located in approximately perpendicular planes and forming corners, a sheet metal strap pivoted to one of said plates on one member for rotation in a plane approximately parallel therewith and having one end bent at right angles to its pivoted portion to extend around a corner, and a catch on one of the plates of the other member perpendicular to the pivoting plate to retain the strap whereby the two members may be detachably interconnected.

65

6. In an inclosed switch, a box comprising a body member and a cover member each having end and side portions at substantial angles to one another to form corners, a flat sheet metal strap having one part lying flat against one of said side portions of one member and secured for rotation about an axis perpendicular thereto as by a pivot, said strap having a bent part adapted to extend around a corner and lie flat against one of the end portions of the other member, and means for connecting the strap to said other member whereby the two members may be detachably interconnected.

75

7. In an inclosed switch, a box comprising a body member and a cover member, a catch pivoted to one of said members and bent to extend around a corner of the box, and a cam projecting from said other member around the corner from the pivoted end of the catch and adapted upon rotation of the catch to be engaged by an edge of the latter to variably tension the same.

85

8. In an inclosed switch, a box comprising a body member and a cover member, a cam projecting from one of said members and a catch pivoted to the other member around a corner of the box from the cam and having a shoulder adapted to be rotated into engagement with the cam to variably tension the catch.

90

CLARENCE D. PLATT.
